UNITED STATES PATENT OFFICE.

JOHN G. MCBRIDE, OF SACRAMENTO, CALIFORNIA.

OIL-CUP.

SPECIFICATION forming part of Letters Patent No. 257,173, dated May 2, 1882.

Application filed December 10, 1881. (No model.)

To all whom it may concern:

Be it known that I, JOHN G. MCBRIDE, of the city and county of Sacramento, in the State of California, have invented certain new and 5 useful Improvements in Oil-Cups; and I do hereby declare that the following is a full, clear, and exact description thereof, reference being had to the accompanying drawings.

The object of my invention is to provide an 10 oil-cup for lubricating journals and bearings in which the feed-regulating devices are all outside of the cup and below it, thus leaving the interior of the cup or oil-reservoir to be wholly occupied by the oil. The feed-regulating 15 device I arrange below the oil reservoir or cup, either horizontally or at an angle to the passage which conducts the oil from the reservoir to the surface to be lubricated, in the manner hereinafter described, and pointed out 20 in the claim.

Referring to the accompanying drawings, Figure 1 is a vertical section with the valve open and held out from the seat. Fig. 2 is a 25 section across the valve-rod, showing the lugs s' and the slots s . Fig. 3 is a section of a portion shown in Fig. 1, the parts being released, the spring expanded, and the valve closed.

Let A represent the cup or oil-reservoir, which can be made in the usual manner and 30 in any desired form.

B is the tubular spindle, which supports the cup above the journal or surface to be lubricated, and through which the oil passes to the said journal or surface. At some point in the length of 35 this spindle I apply the feed-regulating valve, which governs the flow of the oil through the passage, and this valve I arrange at right angles to the passage, so that its handle, stem, or length will extend either horizontally or at an angle, 40 instead of vertically up through the cup or reservoir, as heretofore. I can either apply it at some point between the bottom of the cup and the lower end of the spindle, or I can make the bottom of the cup thicker on one side and 45 arrange the valve so that its spindle will pass through this thickened portion. In the latter case the valve will be very near the upper end of the oil-passage, and the handle or stem will project outside of the body of the cup. Various 50 styles of valves could be used—such, for instance, as a rotary faucet-valve or a gate or cut-off valve; but the best arrangement I have

tried is a common globe-valve operated by a spring, as shown in the drawings, Fig. 1. This arrangement permits me to use my device for 55 regulating and preserving a set-feed shown and described in my Letters Patent No. 221,929, issued to me on the 25th day of November, 1879. In the present instance I have represented the valve as applied below the bottom 60 of the cup in the length of the spindle. The spindle I form with a globular enlargement upon it, and I make the hole or oil-passage e in the upper half of the spindle, on one side of the hole or oil-passage in the lower half, x . 65 I then connect the two passages by an inclined passage, z . In one side of the globular enlargement I make a hole leading to the inclined passage z . I then mount a conical plug or valve, f , so that it will stop up the passage or 70 port z when it is closed down. This valve has a spindle, g , passing outward at an upward angle through a hole in the cap or cover h , and a spring, i , surrounds the spindle, so that one 75 end bears on the plug or valve f , while its opposite end bears against the inside of the cap h , thus serving to keep the plug or valve f on its seat or in any fixed position. When the plug or valve is closed no oil can pass down through the spindle.

On the outside of the cap or cover h , and around the hole through which the spindle passes, I make or form an annular ring, r , as described in my former patent heretofore mentioned, and in this ring I make the recesses or 85 slots s of different depths, as described in that patent.

On the outer end of the screw-threaded spindle I secure the threaded boss or head t , on the under side of which are ribs or lugs s' on a ring, 90 s^2 , that enter the slots or recesses s in the ring r , so that by drawing the spindle outward and turning it so as to drop the ribs or lugs into the recesses corresponding to the feed desired the valve will be opened correspondingly. The 95 oil will then flow down through the oil-passage to the surface to be lubricated.

It will be noticed that this entire arrangement is similar to that described in my former patent, only I arrange the spindle and valve 100 horizontally or at an angle, instead of vertically, and apply it below the oil-cup, thus leaving the interior of the oil cup or reservoir to be occupied solely by the oil.

In the top of the cup A, I make an opening, through which the oil is introduced into the cup, and this opening I stop with an ordinary screw plug or cap, V. This leaves the top of the cup 5 free from any projections, so that it is easily wiped and cleaned, and there is no danger of dirt or dust getting into the reservoir. By placing the mechanism for regulating the flow of oil in the side of the tube rather than down 10 through the top of the oil-reservoir I attain this further advantage: The length of the spring is shortened and its liability to get out of place is greatly diminished. Besides, when located in the reservoir, the surrounding lubricant, if of a stiff and hard character, is apt to 15 obstruct the efficiency of the spring.

Having thus described my invention, what I claim, and desire to secure by Letters Patent, is—

The valve f, stem g, cap h, provided with the 20 ring r, having recesses s, short interposed spring i, and cap t, having a ring, s², provided with lugs s', the whole being arranged in the side of the lubricator-stem, and combined with said stem so as to be adapted for use with the short 25 spring, as herein set forth.

In witness whereof I have hereunto set my hand and seal.

JOHN G. McBRIDE. [L. S.]
